UNITED STATES PATENT OFFICE.

GEORGE W. CUMMINGS, OF TROY, NEW YORK, ASSIGNOR TO ELECTRIC KNITTING CO. INC., OF COHOES, NEW YORK, A CORPORATION OF NEW YORK.

SINKER MECHANISM FOR KNITTING-MACHINES.

1,232,230.

Specification of Letters Patent.

Patented July 3, 1917.

Application filed January 9, 1917. Serial No. 141,470.

To all whom it may concern:

Be it known that I, GEORGE W. CUMMINGS, a citizen of the United States, residing at Troy, county of Rensselaer, and State 5 of New York, have invented certain new and useful Improvements in Sinker Mechanism for Knitting-Machines, of which the following is a specification.

Reference may be had to the accompanying drawings, and the reference characters marked thereon, which form a part of this specification. Similar characters refer to similar parts in the several figures therein.

This invention relates to an improvement 15 upon United States Letters Patent No. 416,256, granted to me December 3, 1889, for a plush bur for knitting machines.

Burs of the character shown and described in said Letters Patent are adapted 20 for use in incorporating in a knitted web of fabric a backing thread having loops exposed on the surface of the web for various purposes.

In the manufacture of certain fabrics the 25 loops formed upon the surface of the knitted web by means of these burs, are brushed to form a plush surface, and the bur shown in my said Letters Patent was adapted to form loops of the backing thread 30 or yarn, of sufficient prominence to give the proper plush surface to the fabric when brushed.

In the use of said prior bur, however, the 35 sinker-fingers, whereby the loops of the backing thread were formed, were forced inwardly to form the loops by engagement of certain of the knitting needles with the respective sinker-fingers. This not only caused a strain upon the needles but limited 40 the length of the loop which could be formed to the depth to which the needles entered between the blades of the yarn-feeding wheel.

In the manufacture of certain knitted 45 fabrics for toweling, wash-cloths and the like, it is desirable to produce upon the surface of the knitted web, numerous loops of thread similar in appearance to, and accomplishing the same purpose as, the loops 50 on woven fabric commonly known as Turkish toweling. Such loops have to be made of much more prominence than the loops which are to be brushed in making the plush surface, and I have found it difficult

to produce loops of sufficient prominence 55 for the present purpose by the use of my prior patented bur.

The principal object of the present invention is to produce the loops of the backing-thread or yarn independently of the knitting-needles, whereby the needles are relieved of the strain of operating the sinker-fingers, and the inward loop-forming movement of the sinker-fingers is not limited to the depth to which the needles enter between 60 the blades of the thread-feeding wheel.

Figure 1 of the drawings is a view in side elevation of my improved sinker-mechanism applied to a spring-needle cylinder knitting-machine, the cylinder being shown 70 in vertical section.

Fig. 2 is a top plan view of the sinker-mechanism detached.

Fig. 3 is a similar view with the thread-feeding wheel detached.

Fig. 4 is a section taken on the broken line 75 4—4 in Fig. 3 in the plane of the axis of the sinker-mechanism.

Referring to the drawings wherein the invention is shown in preferred form, 1 is 80 a stationary support or bracket, mounted adjacent to the cylinder, 2, of a spring-needle cylinder knitting-machine having the usual spring-needles, 3.

A spindle, 4, projects upwardly from the 85 inner end of the support or bracket, 1, forming a means for rotatively mounting the rotatory members of the sinker-mechanism in proper relation to the knitting-needles.

Upon the spindle, 4, is rotatively mounted 90 a thread-or-yarn-feeding wheel, 5, an auxiliary-wheel, 6, and a gear-wheel, 7.

The thread-feeding wheel, 5, is provided with the usual notched blades, 8, forming spaces to engage the knitting-needles, 95 whereby said thread-feeding wheel is rotated by the knitting-needles in the cylinder, causing the yarn or thread to be continuously fed to the needles.

The gear-wheel, 7, has peripherally disposed teeth adapted to mesh with the knitting-needles; and the auxiliary-wheel, 6, is clamped by means of a nut, 9, in fixed relation to said gear-wheel, 7, to rotate therewith.

The auxiliary-wheel, 6, has mounted thereupon sinker-fingers, 10, capable of oscillatory movement substantially as shown and

described in said prior patent, said sinker-fingers being adapted to play in certain of the needle-engaging spaces in the thread-feeding wheel, 5.

These sinker-fingers are adapted to be forced outward at certain times by means of an internal cam 11, nonrotatively mounted upon the spindle, 4, between the thread-feeding wheel, 5, and the auxiliary-wheel, 6, in position to engage the inner side of the sinker-fingers. As a means for causing the inward loop-forming movement of the sinker-fingers, I provide an external cam, 12, fixedly mounted upon the bracket 1, in position to engage the outer side of the sinker-fingers to force them into the respective spaces in the thread-feeding wheel just in advance of the respective needles, causing each sinker-finger to engage the thread or 20 yarn and force a loop of the same into a needle engaged space between two neighboring blades in the thread-feeding wheel.

Where the thread is not thus engaged and looped by the sinker-fingers it is laid along 25 the inner side or back of the needles in the usual manner to incorporate the backing-thread or yarn into the body of the knitted web.

The engagement of the knitting-needles 30 with the thread-feeding wheel, 5, and with the gear-wheel, 7, which is in fixed relation to the auxiliary-wheel, 6, causes all three

wheels to rotate in unison without side-strain upon the sinker-fingers.

By properly proportioning the sinker-fingers and the external cam, 12, the sinker-fingers can be forced inward to any desired extent independently of the knitting-needles, thus making it possible to produce loops of the backing-thread of desired 40 length without respect to the depth to which the knitting-needles enter between the blades of the thread-feeding wheel.

What I claim as new and desire to secure 45 by Letters Patent is—

Sinker-mechanism for knitting-machines having in combination a spindle; a thread-feeding wheel rotatively mounted upon said spindle and provided with spaces for engagement with the knitting-needles; an auxiliary-wheel rotatively mounted upon said spindle; oscillatory sinker-fingers mounted upon said auxiliary-wheel in position to play in certain of the needle-engaging spaces 50 in said thread-feeding wheel; an internal cam nonrotatively mounted upon said spindle between said thread-feeding wheel and said auxiliary-wheel engageable with the inner sides of said sinker-fingers; and an external cam engageable with the outer sides 55 of said sinker-fingers.

In testimony whereof, I have hereunto set my hand this 20th day of December, 1916.

GEORGE W. CUMMINGS.
